CLAIM

The ornamental design for earphones, as shown and described.

DESCRIPTION

FIG. 1 is an exploded perspective view of earphones including a first ear bud and a second ear bud, a remote control, and a jack;

FIG. 2 is a front view of the first ear bud of the earphones of FIG. 1;

FIG. 3 is a right-side view of the first ear bud of the earphones of FIG. 1;

FIG. 4 is a back view of the first ear bud of the earphones of FIG. 1;

FIG. 5 is a left-side view of the first ear bud of the earphones of FIG. 1;

FIG. 6 is a top view of the first ear bud of the earphones of FIG. 1; and,

FIG. 7 is a bottom view of the first ear bud of the earphones of FIG. 1.

The front, right-side, back, left-side, top, and bottom views of the second ear bud being mirror images of the corresponding views of the first ear bud;

The article is not limited to the scale shown herein.

The broken lines are directed to unclaimed portions and form no part of the claimed design.

1 Claim, 2 Drawing Sheets
